UNITED STATES PATENT OFFICE

2,563,011

TWO-PART HUB ADJUSTABLE PITCH FAN

Arthur E. Dehnicke, Lyons, Ill.

Application June 29, 1948, Serial No. 35,882

1 Claim. (Cl. 170—160.6)

1

The present invention relates to a fan and more particularly to a fan having variable pitch blades.

The fan of the present invention may be adapted for use under any circumstances in which a fan having variable pitch blades may be desired, such as for use with condensers, air-conditioning units and like devices. The fan of the present invention is particularly desirable for use in the cooling of internal combustion engines, such as automotive engines, Diesel engines, and the like. In the operation of internal combustion engines, the necessity of operating the engine within a rather limited temperature range is generally appreciated inasmuch as excessive temperatures may cause pre-detonation, "knock" and other operation difficulties, while operation at temperatures below the preferred range may result in condensation of gaseous combustion products within the combustion chamber, excessive combustion chamber deposits and other difficulties. Accordingly, the operation of any given engine within a relatively narrow temperature range is to be greatly desired for most economical and efficient operation. In air cooled engines, or in liquid cooled engines in which the engine is cooled by means of liquid flowing through a conventional radiator and circulation system, the operating temperature of the engine is largely governed by a fan mounted on the forepart of the engine and adapted to create a flow of air over the engine surfaces and/or through the radiator. The amount of air flowing past the engine and/or through the radiator may be regulated by varying the pitch of the fan blade or by varying the rotational speed of the fan.

The present invention provides a fan having variable pitch blades, the fan being adaptable for use with internal combustion engines of either aircooled or liquid cooled type. In the fan of the present invention, the pitch of each of the blades may be simultaneously changed by a very simple adjustment which may be easily and quickly accomplished when the fan is at rest. Positive means are provided for maintaining the pitch of the blades at any given pitch from zero to 360°. The fan of the present invention may be rotated by means of a belt-drive or by means of a shaft axially received by the fan hub.

In general, the fan of the present invention comprises a hub portion, a bevelled ring gear freely rotatable within the hub portion and a plurality of blades carried by the hub portion and extending therebeyond to provide air agitating

2

means and carrying at that end received by the hub bevelled pinions in mesh with the bevelled ring gear carried by the hub. A removable cap portion is provided for the hub and so arranged that it may be clamped against the hub ends of the blades to maintain the blades at any given pitch. The pitch of the blades may be varied by merely loosening the cap portion of the hub, grasping one of the fan blades and rotating the same to change the pitch thereof. The movement of the blade is transmitted through the bevelled pinion carried by the blade to the ring gear freely mounted in the hub and through said ring gear to the bevelled pinions carried by the rest of the blades, so that all of the blades are rotated in the same direction and by the same amount. Thus the pitch of each of the blades may be simultaneously changed with the relative pitch of the blades remaining constant. Following the changing of the pitch of the blades, the blades are clamped in their new position by means of the cap portion of the hub.

It is an important object of the present invention to provide a fan having a plurality of variable pitch blades wherein the pitch of each of the blades may be varied uniformly and in unison by changing the pitch of any one of the blades.

It is a further important object of the present invention to provide a fan comprising a hub, a plurality of blades extending from the hub, intermeshing gears carried by said hub and by said blades for simultaneously adjusting the pitch of all of said blades when the pitch of any one of said blades is changed, and means associated with the hub for clamping the blades in adjusted position.

Other and further important objects of this invention will be apparent from the disclosures in the specification and the accompanying drawings.

On the drawings:

Figure 1 is a fragmentary side elevational view of an internal combustion engine having mounted thereon a fan of the present invention;

Figure 2 is a sectional view, with parts shown in elevation, taken along the line II—II of Figure 1;

Figure 3 is a sectional view, with parts shown in elevation, taken along the line III—III of Figure 2.

As shown on the drawings:

In Figure 1, reference character E refers generally to an internal combustion engine equipped with a fan of the present invention indicated gen-

erally by reference numeral 10. As illustrated, the fan 10 is secured to the engine E by means of a stub-shaft 11 journaled in the bearing 12 and clamped to the engine E by means of a suitable clamp 13. The fan 10 is driven by means of a V-belt 14 looped about the hub 15 of the fan 10 and about the pulley 16 carried by the crank-shaft 17 of the engine E. The fan 10 is thus driven by the engine E, the fan being so positioned that the flow of air induced by the fan is directed over the outer surfaces of the engine E to effectively cool the same. It should be understood that the fan 10 may be employed with a liquid cooled engine to draw air through a radiator and then blow the air across the surfaces of the engine and also that the fan 10 may be mounted upon a shaft connected to the water pump of the engine E rather than to a stub-shaft such as illustrated at 11.

As illustrated in Figure 1, the hub 15 of the fan 10 comprises a body portion 19 and a clamping cap portion 20 secured to the face 24 of the body portion, as by means of cap screws 21, which may be inserted from the front or the back. As illustrated in Figure 3, the hub body portion 19 is generally cylindrical and is axially bored as at 22 to receive the stubshaft 11 secured to the internal combustion engine E. The hub body portion 19 is also provided with an annular groove 23 formed in its outer peripheral face to receive the V-belt 14. The hub 15 may be secured to the shaft 11 for rotation therewith by means of set screws 23a threaded into the hub in the grooves 23 beneath the belt 14. The hub body portion 19, is provided with a circular recess 25 concentric with but having a larger radius than the bore 22 and with a second recessed portion 26 concentric with the recess 25 but of larger radius. That portion of the hub body portion 19 between the concentric recesses 25 and 26 is cut away to define a bevelled shoulder 27. A ring gear 28 having bevelled teeth formed about its outer peripheral face is positioned within the hub body portion 19, to fit into the recess 25 and against the shoulder 27.

The clamping cap 20 is provided with a centrally located recess 29 in that face which abuts the face 24 of the body portion 19, the recess 29 being concentric with and of the same radius as the recess 28 of the body portion 19. The cap 20 is apertured at spaced points about its periphery to receive the cap screws 21 by means of which the cap 20 is clamped to the body portion 19 to form the completed hub structure 15.

The mating faces of the hub body portion 19 and the cap 20 are provided with equally spaced semi-cylindrical apertures 30 and 31 respectively which extend radially outwardly from the recessed portions 26 and 29. As illustrated in Figures 3 and 4 the sets of semi-cylindrical recesses 30 and 31 cooperate to define cylindrical apertures extending from the outer curved surface of the hub 15 into the recesses 26 and 29 to receive the shanks 32 of a plurality of blade-carrying supports 33. The blade-carrying supports 33 are generally cylindrical in form and are slotted at their outer ends as at 34 to receive the fan blades 35. The fan blades 35 are held in the slots 34 by means of rivets 36 or other suitable fastening means which extend through the blade supports 33 and the blades 35.

The inner end of the blade support 33 which extends into the apertures 29 and 26 carries a bevelled pinion 37, either formed integrally with or secured to the shank portion 33. The teeth

of the bevelled pinion 37 are in mesh with the bevelled ring gear teeth of gear 28 and are spaced at equal intervals about the ring gear 28. Although four blades 35, blade supports 34 and bevelled pinion gears 37 are shown, it should be realized that a greater or less number of blades may be employed although the blades should be uniformly spaced about the hub 15.

The ring gear 28 is rotatably seated in the recess 25 and is held therein by means of the bevelled pinions 37 bearing thereagainst. The ring 28 is thus rotatable within the hub 15 and it is obvious that when one of the bevelled pinion gears 37 is rotated, a corresponding rotation is caused in the ring gear 28, and that the rotation of the ring gear 28 causes a corresponding rotation of each of the other bevelled pinions 37. Thus, the rotation of any of the blades 35 will cause a corresponding rotation in each of the other blades 35, the amount of rotation and the direction thereof being equal in each instance.

The cap 20 serves as a means for preventing any accidental change in the pitch of the blades 35 when clamped securely against the face 24 of the hub body portion 19. Thus, when the blades are set at the proper pitch, the cap 20 is clamped tightly against the shanks 32 of the blade support members 33 to prevent further rotation of the blades, the clamping of the cap 20 being accomplished by means of the screws 21. If it is later desired to change the pitch of the blades 35, it is merely necessary to loosen the cap 20 and turn any one of the blades to cause a corresponding and equal rotation in all of the blades 35. If desired, some or all of the recesses 30 and 31 may be cut to define slightly less than a true semi-cylindrical contour, so that proper clamping action of the cap 20 upon the blade shanks 32 may be attained.

Therefore, the present invention provides means whereby the pitch of a number of variable pitch blades in a fan assembly may be changed simultaneously and in equal degree by merely changing the pitch of one of the blades and further provides means whereby the blades may be clamped within the hub assembly to prevent the changing of the pitch of the blades following the setting of the same.

It will, of course, be understood that various details of construction may be varied through a wide range without departing from the principles of this invention and it is, therefore, not the purpose to limit the patent granted hereon otherwise than necessitated by the scope of the appended claim.

I claim as my invention:

A fan comprising a hub having generally cylindrical body and cap portions removably secured together, each of said portions having a concentric generally cylindrical recess formed in one end face thereof, said cylindrical recesses being brought into registry when said portions are assembled to define an interior hub recess, said body and cap each having a plurality of additional semi-cylindrical recesses formed in its concentrically recessed end face and extending radially outwardly from said concentric recess, said semi-cylindrical recesses also being brought into registry upon assembly of said body and cap portions to form a plurality of radially extending cylindrical bores, a bevelled ring gear bottomed within the concentric recess of said body portion, a plurality of blades having shaft portions extending through said radially extending cylindrical bores into said hub recess, and a

beveled pinion on each shank portion in mesh with said ring gear, said ring gear being maintained in rotatable seated engagement within said body portion by the clamping of said shaft portions, said radially extending bores between said body and cap portions to prevent the shifting of pitch of the blades, whereby upon loosening said cap portion a change of pitch of any one of said blades is transmitted through said beveled pinions and said ring gear to each of the other of said blades to accomplish a simultaneous and equal change of pitch in each of said blades.

ARTHUR E. DEHNICKE.
